UNITED STATES PATENT OFFICE.

RICHARD D. GALLAGHER, JR., OF NEW YORK, N. Y.

FRICITION-SPRING.

1,170,146.

Specification of Letters Patent.

Patented Feb. 1, 1916.

Application filed June 19, 1915. Serial No. 35,149.

To all whom it may concern:

Be it known that I, RICHARD D. GALLAGHER, Jr., a citizen of the United States, residing at New York, in the county and State of New York, have invented certain new and useful Improvements in Friction-Springs; and I do hereby declare the following to be a full, clear, and exact description of the same, reference being had to the accompanying drawings, forming part of this specification, and to the figures and letters of reference marked thereon.

This invention relates to improvements in springs, and more particularly to friction springs of the general type disclosed in my Patent No. 1,146,933 granted to me July 20, 1914, the features of the invention, however, being applicable to any structure designed for the purpose of yieldingly resisting the relative movement of parts.

In springs of the type referred to, the main resilient elements, and between which the major portion of the friction is created, are resilient helices, preferably an inner and an outer helix. One helix is nested within the other helix, with the convolutions alternated and lying partially between each other, so as to engage, create friction, and be put under radial stress, by pressure axially of the helices.

The primary object of the present invention is the provision of an improved casing for the main resilient elements of the spring, which, in addition to affording a proper protective covering for the resilient elements, supplements and increases the resistance of the helices to radial expansion under compression and also expands and contracts axially or longitudinally with the helices. Hence, while the helices are maintained in their proper relative positions and their resistance to axial pressure is augmented by the improved casing, with a corresponding increased efficiency of the spring, the possibility of jamming when under stress is avoided by the inherent resiliency of the casing, both radially and axially.

In addition to generally improving the construction of a friction spring, another object of the invention is the provision of a novel arrangement for assembling the caps at each end of the spring, whereby the caps are securely locked against radial, and axial or longitudinal displacement and at the same time are capable of easy detachment, when it is desired to dismount the spring,

A full understanding of the invention will be attained from the ensuing detailed description of a construction embodying the same, in a preferred form when taken in connection with the accompanying drawings, and the novel features of the invention will be particularly pointed out and specified in the appended claims.

In the drawings: Figure 1 is a side elevation of a friction spring embodying the present improvements. Fig. 2 is an axial or longitudinal section taken on planes indicated by the line 2—2 of Fig. 1. Fig. 3 is a side elevation of the spring with the casing in section and showing a preferred arrangement of the outer friction coil. Fig. 4 is an end elevation of the several coils of the spring with the casing removed. Fig. 5 is a fragmentary end elevation looking in the direction of the arrow 5 of Fig. 1. Fig. 6 is a fragmentary end elevation looking in the direction of the arrow 6 of Fig. 1. Fig. 7 is a plan view of the inner face of one of the caps.

Like characters of reference in the several figures indicate the same parts.

The spring illustrated in the accompanying drawings includes the main resilient elements, these consisting of an inner helix 2 and an outer helix 3. Within the main resilient elements is, preferably, helical spring 1. Inner helix 2 is nested within outer helix 3, with the convolutions of outer helix 3 lying partially between the convolutions of inner helix 2. Consequently, when axial pressure is applied to the nested helices, they are put under radial stress, and the convolutions of the helices tend to press toward each other. In the preferred construction the inner helix 2 is provided with oppositely inclined outer friction faces 4 and outer helix 3 is provided with oppositely inclined inner friction faces 5. The inclined friction faces 4 and 5 of the respective helices 2 and 3 are normally in engagement, *i. e.*, when the nested helices are expanded and free from axial stress. Accordingly, when axial pressure is brought to bear on the nested helices, the friction between engaged faces 4 and 5 is greatly increased, resulting in radial expansion of the nested helices. In practice it has been found necessary to construct the outer helix, at least, in sections in order to prevent jamming of the nested friction elements, when under axial stress, and when they are expanding radially. As

shown, in the drawings, the outer helix 3 is made up of a plurality of sections 3^a, 3^b, 3^c. Each section expands radially independently of the other when under stress, and 5 the proximate ends of sections 3^a, 3^b, for instance, separate when radially expanded, and approach each other, when radially contracted. A friction spring constructed of inner and outer nested helices alone, however, does not offer the proper resistance to 10 axial pressure, and, the normal resistance of the nested friction elements, in fact, is materially diminished by constructing the outer helix 3 in sections, since it thereby expands 15 much more freely under stress. The present invention provides a novel casing, surrounding the friction elements, which supplements and increases their resistance to axial pressure and consequent radial expansion, and, at the same time, the casing is 20 inherently resilient both axially and radially so that jamming of the nested elements is avoided. In addition, the casing affords an efficient protective cover for the inner main 25 resilient elements of the spring.

A preferred form of casing is illustrated in the accompanying drawings, reference being made particularly to Figs. 1, 2 and 3. As shown therein, the casing is in the form 30 of a flat helical spring element 6 which almost completely surrounds the inner elements of the spring. It is preferable to construct the casing of a plurality of intercalated flat springs, such as the two intercalated springs 7 and 8 shown. This mode 35 of construction permits each spring to be made of considerably steeper pitch than the inner spring elements, and while affording proper resiliency of the casing, both radially 40 and axially, provides at the same time a substantially continuous casing which provides an adequate protection for the inclosed elements of the spring. The outer faces of 45 the helix 3 are flattened as shown at 3^e to frictionally engage the inner flat faces 7^a, 8^a of the respective casing coils.

The improved casing surrounds and engages the main resilient elements of the spring. While the casing supplements and 50 increases the resistance of the resilient elements to axial stress, its inherent resiliency permits them to expand radially, and prevents jamming under severe strains. In addition, the casing is expansible and contractible 55 axially with the main resilient elements, thereby permitting it to surround them for practically their entire extent, and also greatly increasing the resistance and at the same time, the efficiency of the spring.

60 A further improvement made by the invention is the provision of a novel arrangement for assembling and securely fastening the caps at the respective ends of the spring. When assembled, the caps are not only securely locked against longitudinal displace-

ment when the spring expands and the strain of the expanding coils is brought to bear on the caps, but are also prevented from becoming displaced radially with respect to each other. This permits the caps to be 70 utilized to prevent creeping of the main resilient elements and also of the intercalated flat coils which form the protective casing for the inner elements of the spring. The construction of the caps is best illustrated in 75 Figs. 2, 5, 6 and 7. As shown, the cap 9, at one end of the spring, i. e., to the right of Fig. 2, is provided with a central in-turned sleeve 10, having a longitudinal opening 11. Said longitudinal opening 11 is elongated 80 transversely as shown in Fig. 5, and extends from the outer face of the cap 9 to an inner pin or bar receiving opening 12, substantially circular in cross section and the diameter of which is approximately equal to 85 the smaller transverse dimension of longitudinal opening 11. This construction provides opposed upper and lower flanges 13 and 14 at the inner end of bar receiving opening 12. Extending through opening 12 is the hollow shank 15 of a cap-connecting bar, which bar is passed through the coils of the inner helical spring 1. The end of the shank 15 adjacent cap 9 is provided with a head 16, substantially similar in cross section to the 90 longitudinal opening 11. Said head 16 is received within opening 11 and the inner end of the head adjacent to shank 15 extends oppositely from the shank, as shown in Fig. 2, to provide upper and lower shoulders 17 and 18 which abut against upper and lower flanges 13 and 14, respectively, and limit the inward movement of the bar. As shown in Fig. 2, head 15 is tapered from its inner to 95 its outer end to permit easy insertion and removal of the head in longitudinal opening 11. To facilitate milling of the shank 15 head 16 is also made hollow.

At the opposite end of the spring is a cap 19 having a central in-turned sleeve 20, with a central opening 21 extending from the outer face of the cap to the inner end of sleeve 20. Opening 21 is substantially circular in cross section and its diameter is approximately equal to the diameter of bar-receiving opening 12 of cap 9. Sleeve 20, however, is of the same diameter as sleeve 10 of cap 9. Arranged radially around the circular bore of opening 21 is a series of longitudinal slots 22. Each slot 22 extends from the outer face of cap 19 inwardly part way along opening 21, thus providing a shoulder 23 at the inner end of each slot. The several slots 22 are so spaced about the bore of the opening 21 that one slot is diametrically opposite another slot and accordingly the corresponding shoulders 23 are diametrically opposite each other. The end 24 of shank 15, adjacent to cap 19, is tapered slightly, as shown in Fig. 2, and is provided with a trans-

verse or axially extending squared slot 25 in which is received a key 26. For convenience in milling the tapered end 24 may be bored longitudinally, as shown.

5 In assembling the caps at the opposite ends of the spring, the cap-connecting bar is inserted through cap 9, shank 15 passing through opening 12 of sleeve 10 and head 16 resting against shoulders 13 and 14. 10 Shank 15 extends clear through inner spring 1 and tapered end 24 is projected through opening 21 of sleeve 20. The spring, which is normally longer and of less diameter than the assembled length, is then compressed, and accordingly the caps are forced inwardly 15 toward each other. When transverse slot 25 appears beyond the outer face of cap 19, key 26 is inserted and the respective ends of the key are slipped in any two of the diametrically opposed slots 22. The spring is then 20 allowed to expand, and key 26 slips through the slots and rests on shoulders 23, securely holding cap 19 on the end of the spring. Cap 9 is held by head 16. It will be noted 25 that both caps are securely locked against longitudinal or axial displacement by head 16 and key 26 within slots 22. By providing a plurality of diametrically opposed slots 22, the insertion of key 26 to fasten cap 19 at the 30 end of the spring is greatly facilitated, it only being necessary to slightly shift cap 19 until a pair of diametrically opposed slots are in proper alignment with key 26. When 35 the caps are mounted in this manner the opposite ends of spring 1 rest on the inner faces of the two sleeves 10, 20, and to prevent slipping of the spring its opposite ends 1^a, 1^b are tapered or flattened, as shown.

Each cap is provided with means for preventing 40 creeping of the nested helices and casing coils of the spring, and, inasmuch as the caps are substantially similar in this respect, a description of one will suffice for both. Referring to Fig. 7, the inner face 45 of a cap 9 is provided with opposite outer abutments 27, 28, the respective end faces 27^a, 28^a of which are substantially plane and are engaged by the ends 7^b and 8^b of casing coils 7 and 8. The abutments 27 and 28 50 taper away from their end faces at an angle which conforms substantially to the inclination of the casing coils from the horizontal, and thus provide resting surfaces for the ends of the respective casing coils. The end faces 27^a, 28^a positively prevent creeping of 55 the coils. The coils 7, 8 are tapered as at 7^c, 8^c, in order to permit their ends 7^b, 8^b to properly engage the abutments 27, 28. Within the space confined by the abutments 60 27, 28, is a second abutment 29 having a flat end face 29^a extending radially inwardly to sleeve 10, and a face 29^b opening circumferentially around the cap, and also inwardly toward the center of the cap. Abutment 29 65 is engaged by the end 3^a of outer helix 3.

The inner surface of the cap is furthermore tapered circumferentially as shown at 30 to receive the end 2^a of inner helix 2. The end 2^a of said coil is tapered, as shown, to engage the circumferentially tapered surface 70 30 of the cap. This construction is effective to positively prevent creeping of the several coils of the spring.

What is claimed is:—

1. In a friction spring, the combination of 75 friction spring elements subject to radial expansion under axial stress, and a casing surrounding said friction spring elements comprising a plurality of intercalated coil springs. 80

2. In a friction spring, the combination of 85 a friction element having a cylindrical outer face and said friction element subject to radial expansion under axial stress, and a radially expansible and inherently axially resilient casing having a cylindrical inner face for coöperation with the cylindrical outer face of the friction element, and said casing surrounding said friction element.

3. In a friction spring, the combination 90 of a friction coil having a cylindrical outer face and said coil subject to radial expansion under axial stress, and a radially expansible and inherently axially resilient spring casing having a cylindrical inner 95 face for coöperation with the cylindrical outer face of the friction coil and said spring casing surrounding the friction coil.

4. In a friction spring, the combination 100 of a friction coil subject to radial expansion under axial stress, and a radially and axially, expansible and contractible casing surrounding said friction coil, said casing composed of a plurality of intercalated coil springs. 105

5. The combination of a plurality of resilient helices nested one within the other in position to create friction between the convolutions under axial pressure, the outer helix having a cylindrical outer face, and a casing having a cylindrical inner face for coöperation with the outer cylindrical face of the outer helix to resist radial stress in 110 said helix and also expand and contract axially with said nested helices. 115

6. The combination of a plurality of resilient helices nested one within the other in position to create friction between the convolutions under axial pressure, and a casing composed of a plurality of intercalated coil springs, said casing coils surrounding and frictionally engaging one of 120 said nested helices to resist radial stress in said helices and also expand and contract axially with said helices. 125

7. The combination of a plurality of resilient helices nested one within the other in position to create friction between the convolutions under axial pressure, a casing composed of a plurality of intercalated coil 130

- 41
- springs, said casing coils surrounding and frictionally engaging one of said nested helices to resist radial stress in said helices and also expand and contract axially with said helices, and means for preventing creeping of said casing coils with respect to each other.
8. In a friction spring, the combination of a friction coil subject to radial expansion under axial stress, a casing surrounding said coil comprising a plurality of intercalated coil springs, a cap at each end of the spring, means carried by the caps for preventing creeping of the casing coils with respect to each other, and means for preventing rotation of the caps with respect to each other.
9. In a friction spring, the combination of the main resilient elements, a cap at each end of the spring, a bar extending within said main resilient elements, and connecting said caps, and means carried by said bar for limiting the outward axial movement of the caps and for preventing rotation of the caps with respect to each other.
- 20 10. In a spring, the combination of the main resilient elements, a casing surrounding said spring elements composed of a plurality of intercalated coil springs, a cap at each end of the spring, means carried by the caps for preventing creeping of the casing coils, a bar within said main resilient elements, and connections between said bar and the respective caps for preventing radial displacement of the caps and limiting the outward axial movement of the caps upon expansion of the spring without interfering with movement of the caps toward each others upon compression of the spring.
- 25 11. In a spring, the combination of the main resilient elements, a cap at each end of the spring, a bar within the main resilient elements and upon which the caps are freely movable toward each other upon compression of the spring, and connections between said bar and the caps for preventing radial displacement of the caps and limiting their outward axial movement upon expansion of the spring.
- 30 12. In a spring, the combination of the main resilient elements, a cap at each end of the spring, a bar within the main resilient elements and upon which the caps are freely movable toward each other upon compression of the spring, connections between said bar and the caps for preventing radial displacement of the caps and limiting their

outward axial movement upon expansion of the spring, and means whereby said caps and their connections are assembled on the spring when the resilient elements thereof are compressed.

13. In a spring, the combination of a coil, a cap at each end of the coil, a shank within the coil having a head at one end, a sleeve on one of the caps receiving said head, and said head and sleeve shaped to lock the cap against radial and outward axial displacement on the shank, the other end of the shank extending into a central opening in the other cap, diametrically opposed locking slots in said cap, proximate said opening, and a detachable key inserted transversely in the shank when the coil is compressed, and adapted to rest in said slots to lock said cap against radial and outward axial displacement upon release of the coil.

14. In a spring, the combination of a coil, a cap at each end of the coil, a shank within the coil having a head at one end, a sleeve on one of the caps receiving said head, and said head and sleeve shaped to lock the cap against radial and outward axial displacement on the shank, the other end of the shank extending into a central opening in the other cap, a series of locking slots in said cap extending radially from said opening, and a key carried by the shank and resting in diametrically opposed slcts of the series to lock the cap against radial and outward axial displacement.

15. A friction spring including, in combination, a coil subject to radial expansion under axial stress, and a radially expansible and inherently axially resilient casing surrounding the coil and having a cylindrical inner face for frictional cooperation with the outer face of the coil, the casing arranged to slip relatively to the coil and create friction therewith under pressure in a direction axially of the spring.

16. The combination of a plurality of resilient helices nested one within the other in position to create friction between the convolutions under axial pressure, and a radially expansible and inherently axially resilient casing surrounding the outer helix and having a cylindrical inner face for frictional cooperation with the outer face of the outer helix, the casing arranged to slip relative to the outer helix and create friction therewith under axial pressure.

RICHARD D. GALLAGHER, JR.
